Primary Examiner — Cynthia M. Chin

(57) **CLAIM**

The ornamental design for a toy brick with storage space, as shown and described.

DESCRIPTION

FIG. 1 is a top perspective view of a toy brick with storage space showing my new design;

FIG. 2 is a rear perspective view of the toy brick with storage space;

FIG. 3 is a front view of the toy brick with storage space; and,

FIG. 4 is a top view of the toy brick with storage space, a bottom view thereof forming no portion of the claimed invention.

The broken lines are illustrative of portions of the article forming no portion of the claimed invention.

1 Claim, 3 Drawing Sheets
